UNITED STATES PATENT OFFICE.

ALFRED J. REIF, OF ALLEGHENY, AND ALBERT L. McCORMICK, OF KNOXVILLE, PENNSYLVANIA.

TROLLEY.

No. 852,978.

Specification of Letters Patent.

Patented May 7, 1907.

Application filed June 2, 1906. Serial No. 319,924.

To all whom it may concern:

Be it known that we, ALFRED J. REIF and ALBERT L. McCORMICK, citizens of the United States of America, residing at Allegheny and 5 Knoxville, in the county of Allegheny and State of Pennsylvania, have invented certain new and useful Improvements in Trolleys, of which the following is a specification, reference being had therein to the accompanying 10 drawings.

This invention relates to certain new and useful improvements in attachments for trolley-harps, and the invention has for its main 15 object to provide a simple and inexpensive attachment which will prevent a trolley wheel carried by said harp from being displaced from its trolley-wire or electrical conductor, during the operation of trolley device.

20 The invention further aims to provide a durable and efficient attachment that can be used upon the ordinary harp by simply lengthening the pin thereof, thus permitting of my improved attachment being economically used without incurring any perceptible 25 additional expense, when equipping a car system with said attachments.

The attachment is constructed to prevent 30 a trolley-wheel from being displaced from a trolley-wire by irregularities in the wire, sharp curves, cross-overs, or trolley wire 35 hangers or supports; the attachment receding at each hanger or cross-over and preventing the same from being injured or broken by the attachment.

The detailed construction of the attachment will be hereinafter more fully described and then specifically pointed out in the claims.

40 Referring to the drawing forming part of this specification, like numerals of reference designate corresponding parts throughout the several views, in which

45 Figure 1 is an end view of my improved attachment as applied to a trolley-harp, Fig. 2 is a side elevation of the same, Fig. 3 is a plan of the attachment, Fig. 4 is a side elevation of one of the arms of the attachment, and Fig. 5 is a perspective view of the same.

50 In the accompanying drawing, we have illustrated a conventional form of trolley-harp 1 having a pin 2 mounted transversely thereof, and upon said pin is journaled a trolley-wheel 3. The ends of the pin 2 pro-

trude beyond the side arms 4 of the harp 1 55 and are threaded to receive nuts 5, and pierced to receive cotter-pin 6 to prevent accidental displacement of the nuts.

Our invention resides in providing the ends of the pin 2 with movable lever arms 7, said 60 arms being slotted, as at 8, to permit of said levers being rocked upon the pin 2 and the side arms 4 of the harp 1. The inner faces of the lever arms 7 at the sides of the slots are provided with bearing lugs 9, which engage 65 the side arms 4 of the harp 1 and serve as fulcrums for the movable lever arms 7. The inner faces of the nuts 5 are rounded, as at 10, to form a bearing for the levers when rocked upon the pin 2.

The levers 7 have their upper ends bent inwardly over the harp 1 and wheel 2 into close proximity to one another, to form incline recesses to prevent the trolley-wire 11 from being displaced from the groove of said wheel. 75 The inwardly bent ends 12 of said arms are beveled, as at 14, spaced apart to allow a hanger or wire support to pass between the ends of said arms.

The lower ends of the lever arms 7 are bent 80 outwardly and curved rearwardly, as at 15, and have their extreme ends connected by links 16, to which is fastened a trolley-rope 17, commonly employed for removing a trolley wheel from its wire.

85 The lower ends of the lever arms 7 above the links 16 are connected together by a pin 18 which passes through slots 19 formed in said levers; nuts 20 retaining said pin between said levers. Surrounding the pin 18 is a 90 spring 21 which holds the lever arms 7 against the nuts 20, the upper ends of said levers contiguous to one another, and the links 16 in longitudinal alinement.

95 It is apparent that when the trolley-rope 17, is pulled downwardly, the lever arms 7 will have their upper ends separated allowing the trolley-wheel to be removed from the wire, and upon the rope 17 being released, the spring 21, which has been under tension, 100 will immediately return the lever arms 7 to their normal position.

105 Our attachment is constructed of strong and durable metal, and such changes in the size and minor details of construction as are permissible by the appended claims, may be resorted to without departing from the spirit and scope of the invention.

What we claim and desire to secure by Letters Patent, is:—

The combination with a trolley harp having spaced side arms, of a pin extending transversely through said arms and projecting beyond the same and provided with threaded ends, nuts on said threaded ends of the pin having rounded inner faces, a trolley wheel journaled upon said pin between said harp arms, lever arms swinging upon said pin between the arms of the harp and the nuts on said pin, and provided on their inner faces with curved lugs bearing against the adjacent sides of the harp arms, with their outer faces bearing upon the rounded faces of said nuts, said lever-arms extending inwardly and downwardly at their upper ends

within the channel of the trolley wheel, a tie-rod extending through said lever-arms, a spring on said tie-rod operating to maintain 20 said lever-arms yieldably in distended position at their lower ends, links connecting the lever-arms together adjacent their lower ends, and a rod connected to said links for operating the lever-arms to distend their 25 upper ends.

In testimony whereof we affix our signatures in the presence of two witnesses:

ALFRED J. REIF.

ALBERT L. McCORMICK.
